UNITED STATES PATENT OFFICE.

JESSE G. VINCENT, OF DETROIT, MICHIGAN, ASSIGNOR TO BURROUGHS ADDING MACHINE COMPANY, OF DETROIT, MICHIGAN, A CORPORATION OF MICHIGAN.

ADDING-MACHINE.

968,004.

Specification of Letters Patent. Patented Aug. 23, 1910.

Application filed October 1, 1906. Serial No. 336,922.

To all whom it may concern:

Be it known that I, JESSE G. VINCENT, a citizen of the United States, residing at Detroit, in the county of Wayne and State of Michigan, have invented certain new and useful Improvements in Adding-Machines, of which the following is a specification.

In many types of adding and listing or like machines wherein provision is made for automatically printing a total of amounts accumulated and listed it is necessary before setting the parts for taking a total to put the machine through a blank operation in order to restore the transfer mechanism to normal.

One object of the present invention is to obviate this necessity for putting the machine through a blank operation and to this end it is proposed to provide for restoring the transfer mechanism to normal by the simple act of setting the parts for the taking of a total.

Minor objects of the present invention are to lighten the accumulator structure, simplify and render more durable the transfer tripping devices and improve the form and construction of parts whereby co-operative action is had between individual counting members of the accumulator and the tripping devices of the transfer mechanism.

With these and incidental objects in view the invention consists in certain novel features of construction and combinations of parts the essential elements whereof are recited in the appended claims and a preferred form of embodiment of which is described in detail hereinafter and fully illustrated in the accompanying drawings forming part of this specification.

Of said drawings, Figure 1 represents in left side elevation interior parts of an adding machine of the well-known Burroughs type with the improvements of the present invention applied thereto, the inclosing casing of the machine and cross shafts, rods and certain studs appearing in section, as well as parts of the paper carriage attachment at the rear; Fig. 2 is a similar view on a larger scale of the parts at the front of the machine as relatively positioned at normal; Fig. 3 is a view similar to Fig. 2 but showing the relative positions of parts when the total key has been depressed, dotted lines

illustrating the change in position of some of the parts when the operating handle of 55 the machine has been drawn forward; Figs. 4 and 5 are total elevations illustrating transfer tripping devices under different conditions; Fig. 6 is a horizontal section taken on the line 6—6 of Fig. 3 looking in 60 the direction of the arrows crossing said line; Fig. 7 represents in perspective the accumulator and associated transfer mechanism as viewed from the rear; Fig. 8 represents in longitudinal section on an enlarged scale a portion of the accumulator; 65 and Figs. 9 and 10 represent the accumulator in cross section illustrating different relative positions of transfer and zero stop devices.

By preference the invention has been illustrated as applied to the well known Burroughs adding machine but it is to be understood that it is applicable to other types of machines. For a full and complete understanding of all of the details of the Burroughs machine reference may be had to the Burroughs Patents Nos. 504,963, and 505,078 issued September 12, 1903, and to the Macauley Patent No. 823,474, issued June 12, 1906. It will be sufficient for the 80 purposes of the present specification to briefly enumerate certain well known parts of the Burroughs machine with which the present invention is more particularly concerned and to point out briefly the usual 85 mode of operation of those parts.

The reference numeral 291 designates the usual amount keys and the numeral 610 segmental racks whose extent of movement is determined by stops set by said keys. 90 Small gear wheels or pinions 916 are arranged to mesh with these racks respectively and are compounded with numbered wheels 990 which accumulate the amounts set up on the keyboard. Said pinions and number 95 wheels are carried in a rocking frame having end plates 910 one of which extends below the pivot rod 900 and carries inwardly projecting studs or pins 958 and 958^a one above and the other below said rod. A pitman 914 is branched at the forward end for engagement with these pins or studs and at its rear end connects with a three-armed 100 lever 913 carrying studs or pins 961 arranged to be alternately acted upon by a 105 wipe pawl 821 on the upper end of an arm

813 secured to a rock shaft 800. The latter is oscillated in every operation of the machine and through the devices described the pitman is reciprocated. The latter is connected through a link 911 with a bell crank lever 227 constituting the total key and normally upheld by a suitable spring. So long as this total key is so upheld the reciprocations of the pitman have the effect 5 of removing the accumulator pinions from engagement with the racks at the outset of an operation of the machine and then restoring said pinions to mesh with said racks after the latter have lowered to the extent 10 permitted by depressed amount keys and before the return of said racks to normal. This is due to the fact that normally the stud or pin 958^a rests in a notch at the lower end of the triangular frame like portion of 15 the upper branch of the pitman. Depression of the total key lowers the pitman and destroys this operative connection so that when the pitman is thrust forward as the machine starts to operate the accumulator 20 pinions remain in mesh with the racks. The lowering of the pitman in this manner brings the forward extremity of its lower branch into position for engagement with the stud 958 so that when the pitman moves 25 rearwardly it will rock the accumulator frame and disengage the pinions from the racks before the return movement of the latter commences.

The racks 610 are carried by levers 611 independently pivoted upon a shaft 600 and extended in rear thereof to carry sets of type 618. A swinging frame 613 extends under all the levers 611 and holds the same normally elevated. Said frame swings 30 down and back at every operation of the machine and thus permits lowering of the levers whenever released by the depression of the amount keys or the total key, then operating to restore the levers and racks to 35 normal. The racks are mounted upon the levers with provision for limited movement independent thereof, being slotted to embrace studs on the levers and connected by springs with the latter tending to elevate 40 the racks. The springs are normally restrained however, by detents engaging studs 651 on the racks. These detents, according to the present invention, are in the form of skeleton plates pivoted upon a rod 460 (Fig. 45 7) supported in the rack guide plates 210 and each detent comprises a long arm 413 extending down to one of the accumulator pinions, an arm 413^a extending downwardly and rearwardly at an angle to said long arm 50 for contact with a stop rod 400, a stud 461 for engagement with the rack stud or pin 651 and an arm 413^b projecting forward from the pivot rod 460. The stud 461 is formed with two flat faces 461^a and 461^b extending at an 55 acute angle to each other and meeting in a

sharp edge. Normally the face 461^a engages above the rack stud 651 as shown more clearly in Fig. 4. When the detent is displaced as hereinafter described this face of the stud is moved rearwardly from over said rack stud and the latter may move upwardly along the other flat face 461^b as illustrated in Fig. 5. The stud may be milled to its angular form, hardened and polished and then riveted to a portion of the detent running 60 between the arms 413 and 413^a. This construction permits of more satisfactory manufacturing processes than constructions heretofore employed in the same connection and furthermore possesses advantages in accuracy of operation and in durability.

Each of the accumulator pinions 916 carries a round stud or pin 952 projecting from the side of one tooth and the long arm 413 of the detent plate frame is curved to a limited extent at its lower portion on the arc of 65 said pin 952 (Figs. 9 and 10) and beyond said curved portion has a substantially right angle edge 413^c for said stud or pin to abut when the accumulator wheel turns backward 70 to zero as illustrated in Fig. 9. The right angle edge 413^c forms the upper side of a laterally projecting end of the arm 413, the extremity of which is formed by an edge 413^a extending at an acute angle to the edge 413^c so that the stud 952 may act 75 upon it with a camming effect when the accumulator wheel turns to zero in forward rotation. It will of course be understood that this has the effect of displacing the whole 80 detent structure and carrying the detent stud 461 to the position illustrated in Fig. 5. The above described construction of transfer 85 tripping means possesses advantages over previous constructions in the matter of 90 smoothness and accuracy of operation, friction being reduced to the minimum and an 95 unvarying zero stop action being assured.

The accumulator structure comprises in addition to the parts already enumerated 100 the following described parts which combine to lighten the structure and thus prevent rebound when the accumulator is moved back and forth and furthermore serve to reduce the friction in the bearings of the accumulator wheels. A rod 907 (Figs. 8, 9 and 10) extends between the end plates 910 for the purpose of supporting the wheels and upon this rod are strung a series of sleeves 955 with bushings 939 in their ends and surrounding the rod 907 so as to turn freely 105 thereon. The bushings are of course secured in the sleeves and in this manner a support for each accumulator wheel and gear is provided which turns with the minimum of 110 friction. The sleeves are shouldered to receive the number wheels 990 and the pinions 916 both of which of course turn with the sleeves. Washers 925 are preferably employed 115 secured upon the sleeves against the 120

125 sleeves. Washers 925 are preferably employed secured upon the sleeves against the 130

number wheels as shown in Fig. 8. The supporting rod 907 is preferably screw-threaded at one end to enter a tapped hole in the plate 910 and of course slotted at the other end as shown at 933, which construction facilitates assembling and also taking apart of the structure. A tie-rod 901 extends between the end plates 910 and stay pieces in the form of plates 915 embrace this rod, the pivot rod 900 and the rod 907, these plates occurring between the number wheels and serving to stiffen the structure. Strips 927 and 928 are preferably employed as stringers to unite the stay plates. It will be seen that the above described accumulator structure possesses advantages in reduction of the number of parts without sacrificing strength, but on the contrary working an improvement by reason of lightening this rocking structure.

As in previous constructions, the above described detents are drawn forward by springs 480 and when displaced against the stress of such springs are prevented from immediately returning by the engagement with them of catches drawn rearward by the same springs 480. These catches are in the form of swinging arms 411 depending from a pivot rod and carrying studs 411^a notched in the under sides to normally engage the ends of the detent arms 413^b. When the detents are displaced portions of said studs beyond the notches pass above the arm 413^b and thus prevent immediate return of the detents. The catches have rearwardly and downwardly extending branches 411^b (Fig. 7) arranged to be acted upon by the cross rod 922 of a bail comprising end pieces or arms, one of which 922^L appears in the drawings (Fig. 3) and both of which are secured to a rock shaft 904. The latter has a depending arm 922^a which may be integral with the arm 922^L and is drawn forward by a spring 981 so that the bail is normally retracted. Said depending arm 922^a is pivotally connected with a link 918 whose rear end is widened and slotted in the arc of a circle as shown at 918^a (Fig. 2) to embrace a roller stud 918^b on the arm 813. Through these connections the detent catches are restored to normal at the end of the forward stroke of the operating handle for this brings said arm 813 to the end of its rearward stroke and causes its stud 918^b to draw the link 918 rearwardly thereby rocking the bail forwardly. This takes place in every itemizing operation so that the transfer devices may be restored to normal prior to the addition of a new amount on the accumulator, and as machines of Burroughs and some other types have heretofore been constructed it has been necessary to take a blank stroke in order to operate these connections prior to setting the parts for the taking of a total. As heretofore stated, it is the pur-

pose of the present invention to provide for restoring the transfer mechanism by the act of setting the parts for a total operation which in the present instance consists in depressing the total key.

In carrying out the above stated object of the invention the side arm 922^L of the catch restoring bail is provided with a rearward extension or horn 922^b (Figs. 2 and 3) whose under edge is formed as a cam. The numeral 1400 (Figs. 1, 2 and 3) designates a familiar rock shaft of the Burroughs machine which is oscillated whenever the total key is depressed, this being brought about through the medium of a crank arm 1410 on said crank shaft and a link 1416 connecting said crank arm with the depending arm of the bell crank lever 227. This crank arm in the present instance is formed with a forwardly and upwardly extending branch 1411 carrying a roller stud 1412 which normally occupies a recess in the rear side of the arm 922^L below the horn 922^b. When the total key is depressed the consequent rearward rocking of the crank arm 1410 carries the roller stud 1412 through a short space between it and the cam edge of said horn and then causes said roller stud to act against said edge and thereby force the catch restoring bail forward as illustrated in Fig. 3. It will be seen that this will have the same effect as the rocking of said bail in an operation of the machine viz. that of carrying the notches of the studs 411^a outwardly beyond the extremities of the detent arms 413^b thus permitting the detents to return to effective position. For the purpose of restoring any racks which have performed transfer operations the rock shaft 904 is equipped with a series of forwardly projecting arms 922^c (Figs. 1, 2 and 3) which have a downward curve and present terminal edges for action upon the studs 651. In the normal condition of the machine these studs are held some distance below said terminal edges, being restrained by the detents, but when the detents are displaced and the racks partake of transfer movements the studs are brought up to said terminal edges. Consequently when the total key is depressed and the shaft 904 rocked with the bail in the manner described the arms 922^c moving downward force the racks back to normal position against the stress of their springs. Meantime the catches have been moved in the manner described so that the detents are ready to spring over studs 651 as soon as the latter pass by. The slot 918^a in the link 918 is sufficiently elongated to provide for rearward movement of the link as a result of depression of the total key without requiring movement of the arm 813.

As in a machine such as herein described the accumulator gear wheels or pinions are

normally in mesh with the actuating racks, it is necessary to provide means whereby upon depression of the total key these pinions will be moved out of mesh with the racks in order to permit the restoration of the latter to normal position without affecting the accumulator. To this end the left hand end plate 910 of the accumulator frame is formed with a gear segment 920 and a lever 921 is provided with a similar gear segment 921^a (Figs. 1, 2, 3 and 7) intermeshing with said gear segment 920, said lever being suspended from a pivot point 921^b below the keyboard. This lever has a rearwardly extending branch 921^c equipped with a roller stud 921^d and the total key lever 227 is formed with a depending lug 227^a to which is pivoted a wipe-pawl 227^b having a lateral lip 227^c taking over the front edge 20 of the lug and drawn thereagainst by a spring 227^d. When the total key is depressed this wipe-pawl engages the roller stud 921^d and being held from rearward turning by the engagement of said lip 227^c with the front edge of the lug 227^a, will thrust the lever 921 forward thereby rocking the accumulator structure by reason of the engagement between the gear segments 921^a and 920. The lost motion heretofore referred to as occurring before the roller stud 1412 commences to act upon the horn 922^b allows time for this operation of the lever 921 to take place prior to the action of the arms 922^c upon the racks.

35 Of course it is essential that the accumulator shall return to mesh with the racks before the latter start upon their downward movements in a totalizing operation. To this end the lower branch of the pitman 914, instead of having simply a single prong 914^a as customary, is formed with a second prong 914^b in rear of the prong 914^a with a notch between of such size as to accommodate the stud 958. Upon depression of 40 the total key and consequent lowering of the front end of the pitman the prongs 914^a and 914^b pass down on either side of the stud 958, the latter seating in the notch as illustrated in Fig. 3. Then upon the forward thrust of the pitman, which in the Burroughs machine is timed to occur prior to downward movement of the racks, the rear prong 914^b acting against the stud 958 rocks the accumulator into mesh with the 45 racks as illustrated by the dotted lines in Fig. 3. Of course it will be understood that, as usual in the Burroughs machine, depression of the total key operates through the medium of links 226 and a cross rod 226^a to 50 withdraw latches 415 from engagement with the racks, which latches in itemizing operations are severally withdrawn by the detent slides 214 coöperating with the several banks of keys.

55 It will now be seen that the above de-

scribed constructions are well calculated to thoroughly fulfil the objects primarily stated. At the same time it is to be understood that these constructions are susceptible of variation and that the present invention is not confined to the details thereof.

What is claimed is:

1. In a machine of the character described, the combination of an accumulator comprising a plurality of independently and differentially movable counting members, actuators for the same, transfer devices operating automatically to cause a counting member of higher denomination to advance one step upon the member of next lower denomination having counted up to its capacity, means for taking the total count from the accumulator, and means operating as an incident to the adjustment of parts for taking such total whereby the transfer devices are restored to normal.

2. In a machine of the character described, the combination of an accumulator comprising a plurality of independently and differentially movable counting members, actuators for the same, spring transfer devices operating automatically to cause a counting member of higher denomination to advance one step upon the member of next lower denomination having counted up to its capacity, means for taking the total count from the accumulator, and means operating as an incident to the adjustment of parts for taking such total whereby the transfer devices are restored to normal.

3. In a machine of the character described, the combination of an accumulator comprising a plurality of independently and differentially movable counting members, actuators for the same, transfer devices operating automatically to cause a counting member of higher denomination to advance one step upon the member of next lower denomination having counted up to its capacity, means for restoring the transfer devices to normal in an itemizing operation of the machine, means for taking the total count from the accumulator, and means operating as an incident to the adjustment of parts for taking such total whereby the transfer devices are restored to normal.

4. In a machine of the character described, the combination of an accumulator comprising a plurality of independently and differentially movable counting members, actuators for the same, spring transfer devices operating automatically to cause a counting member of higher denomination to advance one step upon the member of next lower denomination having counted up to its capacity, means for restoring the transfer devices to normal in an itemizing operation of the machine, means for taking the total count from the accumulator, and means operating as an incident to the adjustment of parts for

taking such total whereby the transfer devices are restored to normal.

5. In a machine of the character described, the combination of an accumulator comprising a plurality of independently and differentially movable counting members, actuators for the same, transfer devices operating automatically to cause a counting member of higher denomination to advance one step upon the member of next lower denomination having counted up to its capacity, said devices comprising detents normally preventing transfer movements of the counting members and catches for holding the detents displaced; means for taking the total count from the accumulator, and means operating as an incident to the adjustment of parts for taking such total whereby the transfer catches are restored to normal.

20 6. In a machine of the character described, the combination of an accumulator comprising a plurality of independently and differentially movable counting members, actuators for the same, transfer devices operating automatically to cause a counting member of higher denomination to advance one step upon the member of next lower denomination having counted up to its capacity, said devices comprising spring-pressed detents normally preventing transfer movements of the counting members and catches for holding the detents displaced; means for taking the total count from the accumulator, and means operating as an incident to the adjustment of parts for taking such total whereby the transfer catches are restored to normal.

25 7. In a machine of the character described, the combination of an accumulator comprising a plurality of independently and differentially movable counting members, actuators for the same, transfer devices operating automatically to cause a counting member of higher denomination to advance one step upon the member of next lower denomination having counted up to its capacity, said devices comprising detents normally preventing transfer movements of the counting members and spring-drawn catches for holding the detents displaced; means for taking the total count from the accumulator, and means operating as an incident to the adjustment of parts for taking such total whereby the transfer catches are restored to normal.

30 8. In a machine of the character described, the combination of an accumulator comprising a plurality of independently and differentially movable counting members, actuators for the same, transfer devices operating automatically to cause a counting member of higher denomination to advance one step upon the member of next lower denomination having counted up to its capacity, said devices comprising detents normally preventing transfer movements of the counting

35 members and catches for holding the detents displaced; means for restoring the transfer devices to normal in an itemizing operation of the machine, means for taking the total count from the accumulator, and means operating as an incident to the adjustment of parts for taking such total whereby the transfer catches are restored to normal.

40 9. In a machine of the character described, the combination of an accumulator comprising a plurality of independently and differentially movable counting gear wheels, racks for engaging and turning the same, reciprocating carriers for said racks with provisions for permitting movement thereof independent of the carriers, detents normally preventing such movement but adapted to be displaced when the gear wheels have reached full counting capacity, means for taking the total count from the accumulator, and means operating as an incident to the adjustment of parts for the taking of such total whereby racks which have partaken of movement independent of their carriers are restored to normal.

45 10. In a machine of the character described, the combination of an accumulator comprising a plurality of independently and differentially movable counting gear wheels, racks for engaging and turning the same, reciprocating carriers for said racks with provisions for permitting movement thereof independent of the carriers, detents normally preventing such movement but adapted to be displaced when the gear wheels have reached full counting capacity, catches for holding the detents displaced, means for taking the total count from the accumulator, and means operating as an incident to the adjustment of parts for the taking of such total whereby the detent catches which have acted and racks which have partaken of movement independent of their carriers are restored to normal.

50 11. In a machine of the character described, the combination of an accumulator comprising a plurality of independently and differentially movable counting gear wheels, spring-drawn racks for engaging and turning the same, reciprocating carriers for said racks with provisions for permitting movement thereof independent of the carriage, detents normally preventing such movement but adapted to be displaced when the gear wheels have reached full counting capacity, means for taking the total count from the accumulator, and means operating as an incident to the adjustment of parts for the taking of such total whereby racks which have partaken of movement independent of their carriers are restored to normal.

55 12. In a machine of the character described, the combination of an accumulator comprising a plurality of independently and differentially movable counting gear wheels,

spring-drawn racks for engaging and turning the same, reciprocating carriers for said racks with provisions for permitting movement thereof independent of the carriers, spring-pressed detents normally preventing such movement but adapted to be displaced when the gear wheels have reached full counting capacity, means for taking the total count from the accumulator, and means operating as an incident to the adjustment of parts for the taking of such total whereby racks which have partaken of movement independent of their carriers are restored to normal.

13. In a machine of the character described, the combination of an accumulator comprising a plurality of independently and differentially movable counting gear wheels, spring-drawn racks for engaging and turning the same, reciprocating carriers for said racks with provisions for permitting movement thereof independent of the carriers, spring-pressed detents normally preventing such movement but adapted to be displaced when the gear wheels have reached full counting capacity, spring-drawn catches for holding the detents displaced, means for taking the total count from the accumulator, and means operating as an incident to the adjustment of parts for the taking of such total whereby racks which have partaken of movement independent of their carriers are restored to normal.

14. In a machine of the character described, the combination of an accumulator comprising a plurality of independently and differentially movable counting gear wheels, racks for engaging and turning the same, reciprocating carriers for said racks with provisions for permitting movement thereof independent of the carriers, detents normally preventing such movement but adapted to be displaced when the gear wheels have reached full counting capacity, means for restoring to normal in an itemizing operation of the machine racks which have partaken of movement independent of their carriers, means for taking the total count from the accumulator, and means operating as an incident to the adjustment of parts for the taking of such total whereby racks which have partaken of movement independent of their carriers are restored to normal.

15. In a machine of the character described, the combination of an accumulator comprising a plurality of independently and differentially movable counting gear wheels, racks for engaging and turning the same, reciprocating carriers for said racks with provisions for permitting movement thereof independent of the carriers, detents normally preventing such movement but adapted to be displaced when the gear wheels have reached full counting capacity, catches for holding the detents displaced, means for

restoring to normal in an itemizing operation of the machine racks which have partaken of movement independent of their carriers and catches which have acted, means for taking the total count from the accumulator, and means operating as an incident to the adjustment of parts for the taking of such total whereby the detent catches which have acted and racks which have partaken of movement independent of their carriers are restored to normal. 70 75

16. In a machine of the character described, the combination of an accumulator comprising a plurality of independently and differentially movable counting gear wheels, 80 spring-drawn racks for engaging and turning the same, reciprocating carriers for said racks with provisions for permitting movement thereof independent of the carriers, detents normally preventing such movement 85 but adapted to be displaced when the gear wheels have reached full counting capacity, means for restoring to normal in an itemizing operation of the machine racks which have partaken of movement independent of 90 their carriers, means for taking the total count from the accumulator, and means operating as an incident to the adjustment of parts for the taking of such total whereby racks which have partaken of movement in- 95 dependent of their carriers are restored to normal.

17. In a machine of the character described, the combination of an accumulator comprising a plurality of independently 100 and differentially movable counting gear wheels, spring-drawn racks for engaging and turning the same, reciprocating carriers for said racks with provisions for permitting movement thereof independent of the 105 carriers, spring-pressed detents normally preventing such movement but adapted to be displaced when the gear wheels have reached full counting capacity, means for restoring to normal in an itemizing operation of the machine racks which have partaken of movement independent of their carriers; means for taking the total count from the accumulator, and means operating as an 110 incident to the adjustment of parts for the 115 taking of such total whereby racks which have partaken of movement independent of their carriers are restored to normal.

18. In a machine of the character described, the combination of an accumulator 120 comprising a plurality of independently and differentially movable counting gear wheels, spring-drawn racks for engaging and turning the same, reciprocating carriers for said racks with provisions for permitting movement thereof independent of the carriers, spring-pressed detents normally preventing such movement but adapted to be displaced when the gear wheels have reached full 125 counting capacity, spring-drawn catches for 130

holding the detents displaced, means for restoring to normal in an itemizing operation of the machine racks which have partaken of movement independent of their carriers and catches which have acted, means for taking the total count from the accumulator, and means operating as an incident to the adjustment of parts for the taking of such total whereby the detent catches which have 5 acted and racks which have partaken of movement independent of their carriers are restored to normal.

19. In a machine of the character described, the combination of an accumulator 15 comprising a plurality of independently and differentially movable counting members, actuators for the same, normally engaged therewith, transfer devices operating automatically to cause a counting member of 20 higher denomination to advance one step upon the member of next lower denomination having counted up to its capacity, means for taking the total count from the 25 accumulator, and means operating as an incident to the adjustment of parts for taking such total whereby the accumulator and actuators are disengaged and the transfer devices are restored to normal.

20. In a machine of the character described, the combination of an accumulator 30 comprising a plurality of independently and differentially movable counting gear wheels, racks normally in mesh therewith, reciprocating carriers for said racks with provisions for permitting movement thereof independent of the carriers, detents normally preventing such movement but adapted to be displaced when the gear wheels have 35 reached full counting capacity, means for taking the total count from the accumulator, and means operating as an incident to the adjustment of parts for the taking of such total whereby the gear wheels and racks are 40 disengaged and racks which have partaken of movement independent of their carriers are restored to normal.

21. In a machine of the character described, the combination of an accumulator 45 comprising a plurality of independently and differentially movable counting members, actuators for the same normally engaged therewith, transfer devices operating automatically to cause a counting member of higher denomination to advance one step upon the 50 member of next lower denomination having counted up to its capacity, said devices comprising detents normally preventing transfer movements of the counting members and catches for holding the detents displaced; means for taking the total count from the 55 accumulator, and means operating as an incident to the adjustment of parts for taking such total whereby the accumulator and actuators are disengaged and the transfer 60 catches are restored to normal.

22. In a machine of the character described, the combination of an accumulator comprising a plurality of independently and differentially movable counting gear wheels, racks normally in mesh therewith, 70 reciprocating carriers for said racks with provisions for permitting movement thereof independent of the carriers, detents normally preventing such movement but adapted to be displaced when the gear wheels 75 have reached full counting capacity, catches for holding the detents displaced, means for taking the total count from the accumulator, and means operating as an incident to the adjustment of parts for the taking of 80 such total whereby the gear wheels and racks are disengaged and the detent catches which have acted and racks which have partaken of movement independent of their carriers are restored to normal. 85

23. In a machine of the character described, the combination of an accumulator comprising a plurality of independently and differentially movable counting members, actuators for the same normally engaged 90 therewith, transfer devices operating automatically to cause a counting member of higher denomination to advance one step upon the member of next lower denomination having counted up to its capacity, 95 means for taking the total count from the accumulator, means operating as an incident to the adjustment of parts for taking such total whereby the accumulator and actuators are disengaged and the transfer de- 100 vices are restored to normal and means for reengaging the accumulator and actuators at the outset of a totalizing operation.

24. In a machine of the character described, the combination of an accumulator 105 comprising a plurality of independently and differentially movable counting gear wheels, racks normally in mesh therewith, reciprocating carriers for said racks with provisions for permitting movement thereof independent of the carriers, detents normally preventing such movement but adapted to be displaced when the gear wheels have 110 reached full counting capacity, means for taking the total count from the accumulator, means operating as an incident to the adjustment of parts for the taking of such total whereby the gear wheels and racks are 115 disengaged and racks which have partaken of movement independent of their carriers are restored to normal and means for reengaging the gear wheels and racks at the outset of a totalizing operation. 120

25. In a machine of the character described, the combination of an accumulator 125 comprising a plurality of independently and differentially movable counting gear wheels, racks for engaging and turning the same, a support for the accumulator movable to carry the gear wheels into and out of en- 130

gagement with the racks, means for moving said support with provisions for adjustment to vary the periods of engagement between the accumulator gear wheels and the racks, 5 reciprocating carriers for said racks with provisions for permitting movement thereof independent of the carriers, detents normally preventing such movement but adapted to be displaced when the gear wheels 10 have reached full counting capacity, means for taking the total count from the accumulator through adjustment of the before-mentioned means for moving the accumulator support, and means operating as an incident to the adjustment of parts for the 15 taking of such total whereby the accumulator support is moved to disengage the gear wheels from the racks and racks which have partaken of movement independent of 20 their carriers are restored to normal.

26. In a machine of the character described, the combination of an accumulator comprising a plurality of independently and differentially movable counting members, 25 actuators for the same, transfer devices operating automatically to cause a counting member of higher denomination to advance one step upon the member of next lower denomination having counted up to its capacity, means for taking the total count 30 from the accumulator including a manipulative controlling key, and means operating as an incident to the adjustment of parts for taking such total by manipulation of said 35 controlling key whereby the transfer devices are restored to normal.

27. In a machine of the character described, the combination of an accumulator comprising a plurality of independently and 40 differentially movable counting members, actuators for the same, transfer devices operating automatically to cause a counting member of higher denomination to advance one step upon the member of next lower 45 denomination having counted up to its capacity, means for restoring the transfer devices to normal in an itemizing operation of the machine, means for taking the total count from the accumulator including a 50 manipulative controlling key, and means operating as an incident to the adjustment of parts for taking such total by manipulation of said controlling key whereby the transfer devices are restored to normal.

55. 28. In a machine of the character described, the combination of an accumulator comprising a plurality of independently and differentially movable counting members, actuators for the same, transfer devices operating automatically to cause a counting member of higher denomination to advance one 60 step upon the member of next lower denomination having counted up to its capacity, said devices comprising detents normally preventing transfer movements of the

counting members and catches for holding the detents displaced; means for taking the total count from the accumulator including a manipulative controlling key, and means operating as an incident to the adjustment of parts for taking such total by manipulation of said controlling key whereby the transfer catches are restored to normal. 70

29. In a machine of the character described, the combination of an accumulator comprising a plurality of independently and differentially movable counting members, actuators for the same, transfer devices operating automatically to cause a counting member of higher denomination to advance 75 one step upon the member of next lower denomination having counted up to its capacity, said devices comprising detents normally preventing transfer movements of the counting members and catches for holding 80 the detents displaced; means for restoring the transfer devices to normal in an itemizing operation of the machine, means for taking the total count from the accumulator including a manipulative controlling key, 85 and means operating as an incident to the adjustment of parts for taking such total by manipulation of said controlling key whereby the transfer catches are restored to normal. 90

30. In a machine of the character described, the combination of an accumulator comprising a plurality of independently and differentially movable counting gear wheels, racks for engaging and turning the same, reciprocating carriers for said racks with provisions for permitting movement thereof independent of the carriers, detents normally preventing such movement but adapted to be displaced when the gear wheels have 105 reached full counting capacity, means for taking the total count from the accumulator including a manipulative controlling key, and means operating as an incident to the adjustment of parts for the taking of such 110 total by manipulation of said controlling key whereby racks which have partaken of movement independent of their carriers are restored to normal. 115

31. In a machine of the character described, the combination of an accumulator comprising a plurality of independently and differentially movable counting gear wheels, racks for engaging and turning the same, reciprocating carriers for said racks with provisions for permitting movement thereof independent of the carriers, detents normally preventing such movement but adapted to be displaced when the gear wheels have 120 reached full counting capacity, catches for holding the detents displaced, means for taking the total count from the accumulator including a manipulative controlling key, and means operating as an incident to the adjustment of parts for the taking of such total 125 130

by manipulation of said controlling key whereby the detent catches which have acted and racks which have partaken of movement independent of their carriers are restored to normal.

32. In a machine of the character described, the combination of an accumulator comprising a plurality of independently and differentially movable counting gear wheels, racks for engaging and turning the same, reciprocating carriers for said racks with provisions for permitting movement thereof independent of the carriers, detents normally preventing such movement but adapted to be displaced when the gear wheels have reached full counting capacity, means for restoring to normal in an itemizing operation of the machine racks which have partaken of movement independent of their carriers, means for taking the total count from the accumulator including a manipulative controlling key, and means operating as an incident to the adjustment of parts for the taking of such total by manipulation of said controlling key whereby racks which have partaken of movement independent of their carriers are restored to normal.

33. In a machine of the character described, the combination of an accumulator comprising a plurality of independently and differentially movable counting gear wheels, racks for engaging and turning the same, reciprocating carriers for said racks with provisions for permitting movement thereof independent of the carriers, detents normally preventing such movement but adapted to be displaced when the gear wheels have reached full counting capacity, catches for holding the detents displaced, means for restoring to normal in an itemizing operation of the machine racks which have partaken of movement independent of their carriers and catches which have acted, means for taking the total count from the accumulator including a manipulative controlling key, and means operating as an incident to the adjustment of parts for the taking of such total by manipulation of said controlling key whereby the detent catches which have acted and racks which have partaken of movement independent of their carriers are restored to normal.

34. In a machine of the character described, the combination of an accumulator comprising a plurality of independently and differentially movable counting members, actuators for the same normally engaged therewith, transfer devices operating automatically to cause a counting member of higher denomination to advance one step upon the member of next lower denomination having counted up to its capacity, means for taking the total count from the accumulator including a manipulative con-

trolling key, and means operating as an incident to the adjustment of parts for taking such total by manipulation of said controlling key whereby the accumulator and actuators are disengaged and the transfer devices are restored to normal. 70

35. In a machine of the character described, the combination of an accumulator comprising a plurality of independently and differentially movable counting gear wheels, racks normally in mesh therewith, reciprocating carriers for said racks with provisions for permitting movement thereof independent of the carriers, detents normally preventing such movement but adapted to be displaced when the gear wheels have reached full counting capacity, means for taking the total count from the accumulator including a manipulative controlling key, and means operating as an incident to the adjustment of parts for the taking of such total by manipulation of said controlling key whereby the gear wheels and racks are disengaged and racks which have partaken of movement independent of their carriers are restored to normal. 75 80 85 90

36. In a machine of the character described, the combination of an accumulator comprising a plurality of independently and differentially movable counting members, actuators for the same normally engaged therewith, transfer devices operating automatically to cause a counting member of higher denomination to advance one step upon the member of next lower denomination having counted up to its capacity, said devices comprising detents normally preventing transfer movements of the counting members and catches for holding the detents displaced; means for taking the total count from the accumulator including a manipulative controlling key, and means operating as an incident to the adjustment of parts for taking such total by manipulation of said controlling key whereby the accumulator and actuators are disengaged and the transfer catches are restored to normal. 95 100 105 110

37. In a machine of the character described, the combination of an accumulator comprising a plurality of independently and differentially movable counting gear wheels, racks normally in mesh therewith, reciprocating carriers for said racks with provisions for permitting movement thereof independent of the carriers, detents normally preventing such movement but adapted to be displaced when the gear wheels have reached full counting capacity, catches for holding the detents displaced, means for taking the total count from the accumulator including a manipulative controlling key, and means operating as an incident to the adjustment of parts for the taking of such total by manipulation of said controlling 115 120 125 130

key whereby the gear wheels and racks are disengaged and the detent catches which have acted and racks which have partaken of movement independent of their carriers are restored to normal.

38. In a machine of the character described, the combination of an accumulator comprising a plurality of independently and differentially movable counting members, actuators for the same normally engaged therewith, transfer devices operating automatically to cause a counting member of higher denomination to advance one step upon the member of next lower denomination having counted up to its capacity, means for taking the total count from the accumulator including a manipulative controlling key, means operating as an incident to the adjustment of parts for taking such total by manipulation of said controlling key whereby the accumulator and actuators are disengaged and the transfer devices are restored to normal and means for reengaging the accumulator and actuators at the outset of a totalizing operation.

39. In a machine of the character described, the combination of an accumulator comprising a plurality of independently and differentially movable counting gear wheels, racks normally in mesh therewith, reciprocating carriers for said racks with provisions for permitting movement thereof independent of the carriers, detents normally preventing such movement but adapted to be displaced when the gear wheels have reached full counting capacity, means for taking the total count from the accumulator including a manipulative controlling key, means operating as an incident to the adjustment of parts for the taking of such total by manipulation of said controlling key whereby the gear wheels and racks are disengaged and racks which have partaken of movement independent of their carriers are restored to normal and means for reengaging the gear wheels and racks at the outset of a totalizing operation.

40. In a machine of the character described, the combination of an accumulator comprising a plurality of independently and differentially movable counting gear wheels, racks for engaging and turning the same, a support for the accumulator movable to carry the gear wheels into and out of engagement with the racks, means for moving said support with provisions for adjustment to vary the periods of engagement between the accumulator gear wheels and the racks, said means including a manipulative controlling key, reciprocating carriers for said racks with provisions for permitting movement thereof independent of the carriers, detents normally preventing such movement but adapted to be displaced when the gear wheels have reached full counting capacity, means

for taking the total count from the accumulator through adjustment of the before-mentioned means for moving the accumulator support by manipulation of said controlling key, and means operating as an incident to the adjustment of parts for the taking of such total whereby the accumulator support is moved to disengage the gear wheels from the racks and racks which have partaken of movement independent of their carriers are restored to normal.

41. In a machine of the character described, the combination of an accumulator comprising a plurality of independently and differentially movable counting members, actuators for the same, transfer devices operating automatically to cause a counting member of higher denomination to advance one step upon the member of next lower denomination having counted up to its capacity, said devices comprising detents normally preventing transfer movements of the counting members and catches for holding the detents displaced; means for taking the total count from the accumulator, and means operating as an incident to the adjustment of parts for taking such total whereby the transfer catches are restored to normal, comprising a rock-shaft having a bail to act against the catches.

42. In a machine of the character described, the combination of an accumulator comprising a plurality of independently and differentially movable counting gear wheels, racks for engaging and turning the same, reciprocating carriers for said racks with provisions for permitting movement thereof independent of the carriers, detents normally preventing such movement but adapted to be displaced when the gear wheels have reached full counting capacity, means for taking the total count from the accumulator, and means operating as an incident to the adjustment of parts for the taking of such total whereby racks which have partaken of movement independent of their carriers are restored to normal, said means comprising a rock-shaft having arms to act against the racks.

43. In a machine of the character described, the combination of an accumulator comprising a plurality of independently and differentially movable counting gear wheels, racks for engaging and turning the same, reciprocating carriers for said racks with provisions for permitting movement thereof independent of the carriers, detents normally preventing such movement but adapted to be displaced when the gear wheels have reached full counting capacity, catches for holding the detents displaced, means for taking the total count from the accumulator, and means operating as an incident to the adjustment of parts for the taking of such total whereby the detent catches which have acted and

racks which have partaken of movement independent of their carriers are restored to normal, said means comprising a rock-shaft having arms to act against the racks and a bail to act against the catches.

44. In a machine of the character described, the combination of an accumulator comprising a plurality of independently and differentially movable counting gear wheels, 10 racks for engaging and turning the same, a support for the accumulator movable to carry the gear wheels into and out of engagement with the racks, means for moving said support with provisions for adjustment to vary the periods of engagement between 15 the accumulator gear wheels and the racks, said means including a manipulative controlling key, reciprocating carriers for said racks with provisions for permitting movement thereof independent of the carriers, 20 detents normally preventing such movement but adapted to be displaced when the gear wheels have reached full counting capacity, means for taking the total count from the 25 accumulator through adjustment of the before-mentioned means for moving the accumulator support by manipulation of said controlling key, and means operating as an incident to the adjustment of parts for the 30 taking of such total whereby the accumulator support is moved to disengage the gear wheels from the racks and racks which have partaken of movement independent of their carriers are restored to normal, said means 35 comprising a lever operatively engaged with the accumulator support and a wipe-pawl carried by said controlling key and adapted to engage said lever.

45. In a machine of the character described, the combination of an accumulator comprising a plurality of independently and differentially movable counting gear wheels, 40 racks for engaging and turning the same, a support for the accumulator movable to carry the gear wheels into and out of engagement with the racks said support having a segmental gear, means for moving said support with provisions for adjustment to vary the periods of engagement between the 45 accumulator gear wheels and the racks, said means including a manipulative controlling key, reciprocating carriers for said racks with provisions for permitting movement thereof independent of the carriers, detents 50 normally preventing such movement but adapted to be displaced when the gear wheels have reached full counting capacity, means for taking the total count from the 55 accumulator through adjustment of the before-mentioned means for moving the accumulator support by manipulation of said controlling key, and means operating as an incident to the adjustment of parts for the 60 taking of such total whereby the accumulator support is moved to disengage the gear 65

wheels from the racks and racks which have partaken of movement independent of their carriers are restored to normal, said means comprising a lever having a segmental gear engaging that of the accumulator support, 70 and a wipe-pawl carried by said controlling key and adapted to engage said lever.

46. In a machine of the character described, the combination of an accumulator comprising a plurality of independently 75 and differentially movable counting gear wheels, racks for engaging and turning the same, a support for the accumulator movable to carry the gear wheels into and out of engagement with the racks, means for moving 80 said support with provisions for adjustment to vary the periods of engagement between the accumulator gear wheels and the racks, said means including a manipulative controlling key, reciprocating carriers for said 85 racks with provisions for permitting movement thereof independent of the carriers, detents normally preventing such movement but adapted to be displaced when the gear wheels have reached full counting capacity, 90 means for taking the total count from the accumulator through adjustment of the before-mentioned means for moving the accumulator support by manipulation of said 95 controlling key, and means operating as an incident to the adjustment of parts for the taking of such total whereby the accumulator support is moved to disengage the gear wheels from the racks and racks which have partaken of movement independent of 100 their carriers are restored to normal, said means comprising a lever operatively engaged with the accumulator support, a wipe-pawl carried by said controlling key and adapted to engage said lever, a rock-shaft 105 having arms to engage the racks, and a rock-arm operatively connected with the controlling key and adapted to actuate said rock-shaft.

47. In a machine of the character described, the combination of an accumulator comprising a plurality of independently and differentially movable counting gear wheels, 110 racks for engaging and turning the same, a support for the accumulator movable to carry the gear wheels into and out of engagement with the racks, means for moving said support with provisions for adjustment to vary the periods of engagement between the accumulator gear wheels and the racks, 115 said means including a manipulative controlling key, reciprocating carriers for said racks with provisions for permitting movement thereof independent of the carriers, detents normally preventing such movement but adapted to be displaced when the gear wheels have reached full counting capacity, 120 catches for holding the detents displaced, means for taking the total count from the accumulator through adjustment 125 125

130

of the before-mentioned means for moving the accumulator support by manipulation of said controlling key, and means operating as an incident to the adjustment of parts for the taking of such total whereby the detent catches which have acted and the accumulator support is moved to disengage the gear wheels from the racks and racks which have partaken of movement independent of their carriers are restored to normal, said means comprising a lever operatively engaged with the accumulator support, a wipe-pawl carried by said controlling key and adapted to engage said lever, a rock-shaft having arms to engage the racks and a bail to engage the catches, and a rock-arm operatively connected with the controlling key and adapted to actuate said rock-shaft.

48. In a machine of the character described, the combination of an accumulator comprising a plurality of independently and differentially movable counting gear wheels, racks for engaging and turning the same, a support for the accumulator movable to carry the gear wheels into and out of engagement with the racks, means for moving said support with provisions for adjustment to vary the periods of engagement between the accumulator gear wheels and the racks, said means including a manipulative controlling key in the form of a bell-crank lever, reciprocating carriers for said racks with provisions for permitting movement thereof independent of the carriers, detents normally preventing such movement but adapted to be displaced when the gear wheels have reached full counting capacity, catches for holding the detents displaced, means for taking the total count from the accumulator through adjustment of the before-mentioned means for moving the accumulator support by manipulation of said controlling key, and means operating as an incident to the adjustment of parts for the taking of such total whereby the detent catches which have acted and the accumulator support is moved to disengage the gear wheels from the racks and racks which have partaken of movement independent of their carriers are restored to normal, said means comprising a rock-shaft having a bail to act against the catches, a rock-arm to actuate said rock-shaft, and a link connecting said rock-arm and the bell-crank lever.

49. In a machine of the character described, the combination of an accumulator comprising a plurality of independently and differentially movable counting gear wheels, racks for engaging and turning the same, a support for the accumulator movable to carry the gear wheels into and out of engagement with the racks, means for moving said support with provisions for adjustment to vary the periods of engagement between the accumulator gear wheels and

the racks, said means including a manipulative controlling key in the form of a bell-crank lever, reciprocating carriers for said racks with provisions for permitting movement thereof independent of the carriers, detents normally preventing such movement but adapted to be displaced when the gear wheels have reached full counting capacity, catches for holding the detents displaced, means for taking the total count from the accumulator through adjustment of the before-mentioned means for moving the accumulator support by manipulation of said controlling key, and means operating as an incident to the adjustment of parts for the taking of such total whereby the detent catches which have acted and the accumulator support is moved to disengage the gear wheels from the racks and racks which have partaken of movement independent of their carriers are restored to normal, said means comprising a lever operatively engaged with the accumulator support, a wipe-pawl carried by said controlling key and adapted to engage said lever, a rock-shaft having arms to engage the racks and a bail to engage the catches, and a rock-arm operatively connected with the controlling key and adapted to actuate said rock-shaft.

50. In a machine of the character described, the combination of reciprocating rack-carriers, racks thereon movable to a limited extent independently thereof, an accumulator frame centrally pivoted, an accumulator mounted in said frame on one side of its pivot and comprising gear wheels normally in mesh with said racks respectively and transfer trippers compounded with said wheels, a reciprocating pitman constructed for engagement with said frame on opposite sides of the latter's pivot to rock it back and forth under either engagement and shiftable to disengage on one side of the pivot and engage on the other, detents normally holding the racks against movement independent of their carriers and adapted to be displaced by the transfer trippers, total-controlling devices for shifting the pitman to disable the normal connection between the same and the accumulator frame for disengaging the gear wheels from the racks at the outset of an itemizing operation, means actuated by said controlling devices to effect such disengagement and means subsequently actuated by said controlling devices to restore to normal any racks which have moved independently of their carriers, the shifting of the pitman engaging it with the accumulator frame in such manner as to reengage the gear wheels with the racks at the outset of an operation of the machine.

51. In a machine of the character described, the combination of reciprocating rack-carriers, racks thereon movable to a limited extent independently thereof, an accumulator frame centrally pivoted, an accumulator mounted in said frame on one side of its pivot and comprising gear wheels normally in mesh with said racks respec-

- tively and transfer trippers compounded with said wheels, a reciprocating pitman constructed for engagement with said frame on opposite sides of the latter's pivot to rock it back and forth under either engagement and shiftable to disengage on one side of the pivot and engage on the other, detents normally holding the racks against movement independent of their carriers and adapted to be displaced by the transfer trippers, total-controlling devices for shifting the pitman to disable the normal connection between the same and the accumulator frame for disengaging the gear wheels from the racks at the outset of an itemizing operation, a lever actuated by said controlling devices to effect such disengagement and means subsequently actuated by said controlling devices to restore to normal any racks which have moved independently of their carriers, the shifting of the pitman engaging it with the accumulator frame in such manner as to reengage the gear wheels with the racks at the outset of an operation of the machine.
52. In a machine of the character described, the combination of reciprocating rack-carriers, racks thereon movable to a limited extent independently thereof, an accumulator frame centrally pivoted, an accumulator mounted in said frame on one side of its pivot and comprising gear wheels normally in mesh with said racks respectively and transfer trippers compounded with said wheels, a reciprocating pitman constructed for engagement with said frame on opposite sides of the latter's pivot to rock it back and forth under either engagement and shiftable to disengage on one side of the pivot and engage on the other, detents normally holding the racks against movement independent of their carriers and adapted to be displaced by the transfer trippers, total-controlling devices for shifting the pitman to disable the normal connection between the same and the accumulator frame for disengaging the gear wheels from the racks at the outset of an itemizing operation, a lever actuated by said controlling devices to effect such disengagement, said lever having a segmental gear to mesh with that of the accumulator support, and means subsequently actuated by said controlling devices to restore to normal any racks which have moved independently of their carriers, the shifting of the pitman engaging it with the accumulator frame in such manner as to reengage the gear wheels with the racks at the outset of an operation of the machine.
53. In a machine of the character described, the combination of reciprocating rack-carriers, racks thereon movable to a limited extent independently thereof, an accumulator frame centrally pivoted, an accumulator mounted in said frame on one side of its pivot and comprising gear wheels normally in mesh with said racks respectively and transfer trippers compounded with said wheels, a reciprocating pitman constructed for engagement with said frame on opposite sides of the latter's pivot to rock it back and forth under either engagement and shiftable to disengage on one side of the pivot and engage on the other, detents normally holding the racks against movement independent of their carriers and adapted to be displaced by the transfer trippers, total-controlling devices for shifting the pitman to disable the normal connection between the same and the accumulator frame for disengaging the gear wheels from the racks at the outset of an itemizing operation, means actuated by said controlling devices to effect such disengagement and a rock-shaft subsequently actuated by said controlling devices and having arms engaging the racks and operating to restore to normal any racks which have moved independently of their carriers, the shifting of the pitman engaging it with the accumulator frame in such manner as to reengage the gear wheels with the racks at the outset of an operation of the machine.
54. In a machine of the character described, the combination of reciprocating rack-carriers, racks thereon movable to a limited extent independently thereof, an accumulator frame centrally pivoted, an accumulator mounted in said frame on one side of its pivot and comprising gear wheels normally in mesh with said racks respectively and transfer trippers compounded with said wheels, a reciprocating pitman constructed for engagement with said frame on opposite sides of the latter's pivot to rock it back and forth under either engagement and shiftable to disengage on one side of the pivot and engage on the other, detents normally holding the racks against movement independent of their carriers and adapted to be displaced by the transfer trippers, total-controlling devices for shifting the pitman to disable the normal connection between the same and the accumulator frame for disengaging the gear wheels from the racks at the outset of an itemizing operation, a lever actuated by said controlling devices to effect such disengagement and a rock-shaft subsequently actuated by said controlling devices and having arms engaging the racks and operating to restore to normal any racks which have moved independently of their carriers, the shifting of the pitman engaging it with the accumulator frame in such manner as to reengage the gear wheels with the racks at the outset of an operation of the machine.
55. In a machine of the character described, the combination of reciprocating rack-carriers, racks thereon movable to a limited extent independently thereof, an accumulator frame centrally pivoted and having a segmental gear, an accumulator mounted in said frame on one side of its

rack-carriers, racks thereon movable to a limited extent independently thereof, an accumulator frame centrally pivoted, an accumulator mounted in said frame on one side of its pivot and comprising gear wheels normally in mesh with said racks respectively and transfer trippers compounded with said wheels, a reciprocating pitman constructed for engagement with said frame on opposite sides of the latter's pivot to rock it back and forth under either engagement and shiftable to disengage on one side of the pivot and engage on the other, detents normally holding the racks against movement independent of their carriers and adapted to be displaced by the transfer trippers, catches adapted to engage the detents to hold the same displaced, total-controlling devices for shifting the pitman to disable the normal connection between the same and the accumulator frame for disengaging the gear wheels from the racks at the outset of an itemizing operation, means actuated by said controlling devices to effect such disengagement and a rock-shaft subsequently actuated by said controlling devices and having arms engaging the racks and operating to restore to normal any racks which have moved independently of their carriers and also having a bail acting to restore the catches to normal, the shifting of the pitman engaging it with the accumulator frame in such manner as to reengage the gear wheels with the racks at the outset of an operation of the machine.

56. In a machine of the character described, the combination of reciprocating rack-carriers, racks thereon movable to a limited extent independently thereof, an accumulator frame centrally pivoted, an accumulator mounted in said frame on one side of its pivot and comprising gear wheels normally in mesh with said racks respectively and transfer trippers compounded with said wheels, a reciprocating pitman constructed for engagement with said frame on opposite sides of the latter's pivot to rock it back and forth under either engagement and shiftable to disengage on one side of the pivot and engage on the other, detents normally holding the racks against movement independent of their carriers and adapted to be displaced by the transfer trippers, a total key for shifting the pitman to disable the normal connection between the same and the accumulator frame for disengaging the gear wheels from the racks at the outset of an itemizing operation, a lever engaged with the accumulator frame to effect such disengagement, a wipe-pawl carried by the total key and adapted to engage and operate said lever, and means subsequently actuated by said controlling devices to restore to normal any racks which

have moved independently of their carriers, the shifting of the pitman engaging it with the accumulator frame in such manner as to reengage the gear wheels with the racks at the outset of an operation of the machine.

57. In a machine of the character described, the combination of reciprocating rack-carriers, racks thereon movable to a limited extent independently thereof, an accumulator frame centrally pivoted, an accumulator mounted in said frame on one side of its pivot and comprising gear wheels normally in mesh with said racks respectively and transfer trippers compounded with said wheels, a reciprocating pitman constructed for engagement with said frame on opposite sides of the latter's pivot to rock it back and forth under either engagement and shiftable to disengage on one side of the pivot and engage on the other, detents normally holding the racks against movement independent of their carriers and adapted to be displaced by the transfer trippers, catches adapted to engage the detents to hold the same displaced, a total lever for shifting the pitman to disable the normal connection between the same and the accumulator frame for disengaging the gear wheels from the racks at the outset of an itemizing operation, means actuated by said lever to effect such disengagement, a rock-shaft subsequently actuated by said lever and having arms engaging the racks and operating to restore to normal any racks which have moved independently of their carriers, the shifting of the pitman engaging it with the accumulator frame in such manner as to reengage the gear wheels with the racks at the outset of an operation of the machine, and a rock-arm connected with the total lever for operating said rock-shaft.

58. In a machine of the character described, the combination of reciprocating rack-carriers, racks thereon movable to a limited extent independently thereof, an accumulator frame centrally pivoted, an accumulator mounted in said frame on one side of its pivot and comprising gear wheels normally in mesh with said racks respectively and transfer trippers compounded with said wheels, a reciprocating pitman constructed for engagement with said frame on opposite sides of the latter's pivot to rock it back and forth under either engagement and shiftable to disengage on one side of the pivot and engage on the other, detents normally holding the racks against movement independent of their carriers and adapted to be displaced by the transfer trippers, a total lever for shifting the pitman to disable the normal connection between the same and the accumulator frame for disengaging the gear wheels from the racks at the outset of an itemizing operation, means actuated by said lever to effect such disengagement, a rock-

shaft subsequently actuated by said total lever and having arms engaging the racks and operating to restore to normal any racks which have moved independently of their carriers, said rock-shaft also having a cam-arm, the shifting of the pitman engaging it with the accumulator frame in such manner as to reengage the gear wheels with the racks at the outset of an operation of the machine 10 and a rock-arm connected with the total lever for operating said rock-shaft by acting against the cam-arm thereof.

59. In a machine of the character described, the combination of reciprocating rack-carriers, racks thereon movable to a limited extent independently thereof, an accumulator frame centrally pivoted, an accumulator mounted in said frame on one side of its pivot and comprising gear wheels 20 normally in mesh with said racks respectively and transfer trippers compounded with said wheels, a reciprocating pitman constructed for engagement with said frame on opposite sides of the latter's pivot to rock it back and forth under either engagement 25 and shiftable to disengage on one side of the pivot and engage on the other, detents normally holding the racks against movement independent of their carriers and adapted 30 to be displaced by the transfer trippers, a total lever for shifting the pitman to disable the normal connection between the same and the accumulator frame for disengaging the gear wheels from the racks at the outset 35 of an itemizing operation, means actuated by said controlling devices to effect such disengagement, a rock-shaft subsequently actuated by said controlling devices and having arms engaging the racks and operating to 40 restore to normal any racks which have moved independently of their carriers, said rock-shaft also having a bail acting to restore the catches to normal and a cam-arm, the shifting of the pitman engaging it with 45 the accumulator frame in such manner as to reengage the gear wheels with the racks at the outset of an operation of the machine; and a rock-arm connected with the total lever for operating said rock-shaft by acting 50 against the cam-arm thereof.

60. In a machine of the character described, the combination of reciprocating rack-carriers, racks thereon movable to a limited extent independently thereof, an accumulator frame centrally pivoted, an accumulator mounted in said frame on one side of its pivot and comprising gear wheels 55 normally in mesh with said racks respectively and transfer trippers compounded with said wheels, a reciprocating pitman constructed for engagement with said frame on opposite sides of the latter's pivot to rock it back and forth under either engagement 60 and shiftable to disengage on one side of the

pivot and engage on the other, detents normally holding the racks against movement independent of their carriers and adapted to be displaced by the transfer trippers, total-controlling devices for shifting the pitman to disable the normal connection between the same and the accumulator frame for disengaging the gear wheels from the racks at the outset of an itemizing operation, means actuated by said controlling devices to effect such disengagement, means 65 subsequently actuated by said controlling devices to restore to normal any racks which have moved independently of their carriers, the shifting of the pitman engaging it with the accumulator frame in such manner as to reengage the gear wheels with the racks at the outset of an operation of the machine; and means acting in an itemizing operation of the machine to restore the racks to normal. 70

61. In a machine of the character described, the combination of reciprocating rack-carriers, racks thereon movable to a limited extent independently thereof, an accumulator frame centrally pivoted, an accumulator mounted in said frame on one 80 side of its pivot and comprising gear wheels normally in mesh with said racks respectively and transfer trippers compounded with said wheels, a reciprocating pitman constructed for engagement with said frame on opposite sides of the latter's pivot to rock it back and forth under either engagement 85 and shiftable to disengage on one side of the pivot and engage on the other, detents normally holding the racks against movement 90 independent of their carriers and adapted to be displaced by the transfer trippers, catches adapted to engage the detents to hold the same displaced, total-controlling devices for shifting the pitman to disable the normal connection between the same and the accumulator frame for disengaging the gear wheels from the racks at the outset of an itemizing operation, means actuated by said controlling devices to effect such disengagement, 95 a rock-shaft subsequently actuated by said controlling devices and having arms engaging the racks and operating to restore to normal any racks which have moved independently of their carriers and also having a bail acting to restore the catches to 100 normal, the shifting of the pitman engaging it with the accumulator frame in such manner as to reengage the gear wheels with the racks at the outset of an operation of the machine; and means acting in an itemizing operation of the machine to turn the rock-shaft and restore the catches to normal. 110

62. In a machine of the character described, an accumulator structure comprising end plates or arms, a rod supported at its ends in said plates, sleeves strung upon said rod with bushings in their ends, wheels 115 120 125

secured on said sleeves, a tie-rod extending between the end plates, and stay pieces extending between said tie-rod and the sleeve-carrying rod at intervals.

5 63. In a machine of the character described, an accumulator structure comprising end plates or arms, a rod supported at its ends in said plates, sleeves strung upon said rod with bushings in their ends, wheels secured on said sleeves, a tie-rod extending between the end plates, a pivot rod extending between the end plates and stay pieces extending at intervals between said sleeve-carrying rod, said tie-rod and said pivot-
5 rod.

64. In a machine of the character described, the combination of an accumulator wheel having a laterally projecting round transfer pin or stud, and a pivoted transfer
0 and zero stop arm having an end portion with a cam edge for said pin or stud to act upon in displacing the arm for transfer purposes and a right angle edge for said pin or stud to abut when the wheel turns back-
5 ward to zero.

65. In a machine of the character described, the combination of an accumulator wheel having a transfer projection, an actu-

ator for said wheel spring-drawn for transfer purposes and having a laterally projecting stud or pin, and a swinging transfer arm adapted to be displaced by the transfer projection on the wheel and having a laterally projecting angularly-faced stud one flat side of which normally engages the laterally projecting stud or pin of the actuator to prevent movement thereof, the displacement of the transfer arm permitting said actuator stud or pin to move along the other flat face of the transfer arm stud.

66. In a machine of the character described, the combination with a prime mover and its operating connections, accumulating and total-taking mechanism including transfer devices, and manipulative controlling devices for said mechanism; of means for restoring the transfer devices to normal through manipulation of said controlling devices preliminary to the taking of a total by operation of the prime mover and its connections.
